UNITED STATES PATENT OFFICE.

HARRY H. SCHROYER, OF CHICAGO, ILLINOIS, ASSIGNOR TO THE ACME SUPPLY COMPANY, A CORPORATION OF ILLINOIS.

WEATHER-STRIP.

1,094,481.

Specification of Letters Patent. Patented Apr. 28, 1914.

Application filed March 12, 1913. Serial No. 753,760.

To all whom it may concern:

Be it known that I, HARRY H. SCHROYER, a citizen of the United States, and a resident of the city of Chicago, in the county of 5 Cook and State of Illinois, have invented certain new and useful Improvements in Weather-Strips; and I do hereby declare that the following is a full, clear, and exact description of the same, reference being had 10 to the accompanying drawings, and to the numbers of reference marked thereon, which form a part of this specification.

This invention relates to new and useful improvements in weather strips, and although applicable for general use, is shown 15 more particularly embodied as a weather strip or guard for car windows.

It is an important object of this invention to provide a weather strip adapted to prevent air or dust from entering between the 20 lower rail and the sill of the window when the sash is closed.

It is also an object of this invention to provide a flexible fabric sealing means 25 adapted to seal the space between the sash rail and the sill along a plurality of lines.

It is also an object of this invention to provide a weather strip in which the weight 30 of the sliding sash and the wind pressure thereon serves to make the seal more effective.

It is finally an important object of this invention to provide a simple, durable and inexpensive weather strip adaptable to any 35 ordinary sash without alteration thereof and to afford an effectual seal therefor.

The invention (in a preferred form) consists in the matters hereinafter described and more fully pointed out and defined in 40 the appended claims.

In the drawings: Figure 1 is a fragmentary view in elevation illustrating the outside of a car window equipped with a device embodying the principles of my invention. 45 Fig. 2 is an enlarged fragmentary section through the sash rails and sill thereof. Fig. 3 is an enlarged detail view in section of the lower sash rail and the sill with the weather stripping engaged therebetween. 50 Fig. 4 is an enlarged sectional view of the lower rail of the window sash, illustrating the operation of the weather stripping when the window rail is out of contact with the

sill. Fig. 5 is a fragmentary bottom plan view of the window rail with the weather 55 stripping secured thereon.

As shown in the drawings: the reference numeral 1 indicates an ordinary sloping outside window sill of a car window secured in a suitable manner to an inside sill numbered as 2. As shown in Fig. 2, the car window consists of a double sash comprising an inner and outer sliding sash member numbered as 3 and 4, respectively. The weather stripping means is secured on the 65 lower rail of the outer sash and comprises a base plate 5, secured to the lower face of the sash rail, and, if desired, said plate is folded over and back upon itself as shown at 6. The other edge of said plate is bent at 70 an acute angle as shown at 7, for a purpose hereinafter set forth. A strip of tallow-sealed or otherwise impregnated felt 8, is secured tightly against said plate 5, by means of a metallic strip 9, which is secured 75 to and through the plate 5, and into the sash rail 4, by means of the screws 10. Said strip of fabric, as shown, is of such a length as to afford depending ends 11 and 12, which serve to seal the rail and sill at two points. 80

The operation is as follows: As shown in the drawings, the lower rails of the sliding sashes are faced at an angle to correspond with the slope of the sill member 1. When the sash is opened the depending edges 11 85 and 12, of the fabric hang slightly inclined from perpendicular, the slight stiffness of the fabric tending to hold the edge 11, slightly outwardly and the acute angled flange 7, of the plate 5, serving to bend the 90 edge 12, of the fabric in substantially parallel relation with the depending edge 11.

When the window sash is closed, as the rail 3 approaches the sill, the edge 12 of the fabric striking the surface of the sill 95 is directed beneath the plate 9, while the edge 11, being similarly directed, is thrust outwardly and extends for a short distance downwardly on the face of the sill. Thus it is seen that the weight of the sash serves 100 to compress the edge 12, of the fabric therebeneath to afford a seal. The other edge 11 of the fabric extending outwardly as it does upon the sill, due to its slight stiffness, bears 105 upon the same in close relation, but the contact pressure thereof upon the sill is more

importantly and further augmented by the pressure of the wind acting upon the same when the train is in motion.

Of course, details of construction are open to wide variation without departing from the principles of this invention, and I therefore do not purpose limiting the patent granted otherwise than necessitated by the prior art.

10 I claim as my invention:

1. In a device of the class described, a base plate adapted to be secured to the lower rail of a sash and having an angled flange at one edge thereof, a strip secured to said base plate, and a piece of fabric secured between said base plate and strip with its edges depending, said angled flange directing one of said depending edges inward beneath said strip, and said other edge being left free to project beyond the sash rail.
- 15
- 20

2. In a device of the class described, a base plate adapted to be secured to the lower edge of a sash and coextensive in width therewith and having an angled flange at the inner edge thereof, a narrower strip secured to said base plate, and a piece of fabric secured between said base plate and strip with its edges depending, said angled flange directing one of said depending edges inward beneath said strip, and said other edge being left free to project beyond the sash rail.

In testimony whereof I have hereunto subscribed my name in the presence of two subscribing witnesses.

HARRY H. SCHROYER.
